UNITED STATES PATENT OFFICE

90,772

DESIGN FOR A POINTER KNOB

Henry J. Kasch, Dayton, Ohio, assignor to The Kurz-Kasch Company, Dayton, Ohio, a corporation of Ohio

Application June 15, 1933. Serial No. 48,413

Term of patent 7 years

To all whom it may concern:

Be it known that I, HENRY J. KASCH, a citizen of the United States, residing at Dayton, Montgomery County, Ohio, have invented a new, original, and ornamental Design for a Pointer Knob, of which the following is a specification, reference being had to the accompanying drawing, forming a part hereof.

Fig. 1 is a perspective view of a pointer knob illustrating my new design. Fig. 2 is a top plan view. Fig. 3 is a side elevation. Fig. 4 is a profile of the knob design.

The dominant feature of the knob design, forming the subject matter hereof, is a polygonal body of which two converging spaced sides are extended into intersection with each other to form an angular beak to serve as a pointer or indicator.

I claim:

The ornamental design for a pointer knob, substantially as shown and described.

In testimony whereof, I have hereunto set my hand this 5th day of May, 1933.

HENRY J. KASCH.
